UNITED STATES PATENT OFFICE.

JOHN T. HAYNE, OF DETROIT, MICHIGAN.

DESIGN FOR A MAT FOR AUTOMOBILE RUNNING-BOARDS.

53,737.

Specification for Design.

Patented Aug. 26, 1919.

Application filed March 31, 1919. Serial No. 286,576. Term of patent 14 years.

To all whom it may concern:

Be it known that I, JOHN T. HAYNE, residing at Detroit, in the county of Wayne and State of Michigan, have invented a new, original, and ornamental Design for a Mat for Automobile Running-Boards, of which the following is a specification, reference being had to the accompanying drawings, forming part thereof.

Figure 1 is a perspective view showing my new mat design.

Copies of this patent may be obtained for five cents each, by addressing the "Commissioner of Patents, Washington, D. C."

Fig. 2 is a cross section taken on the dotted line A—A Fig. 1.

I claim:—

The ornamental design for a mat for automobile running boards, as shown.

March 29, 1919.

JOHN T. HAYNE.
